UNITED STATES PATENT OFFICE

158,811

RAILWAY CAR SHAKER OR SIMILAR ARTICLE

Yngve Soderberg, Chicago, Ill.

Application January 15, 1949, Serial No. 250

Term of patent 14 years

(Cl. D41—1)

To all whom it may concern:

Be it known that I, Yngve Soderberg, a citizen of the United States, residing in the city of Chicago, State of Illinois, have invented a new, original, and ornamental Design for a Railway Car Shaker or Similar Article, of which the following is a specification, reference being had to the accompanying drawing, forming a part hereof.

Fig. 1 is a front perspective view of a railway car shaker, showing my new design.

Fig. 2 is a rear perspective view thereof.

Fig. 3 is a front elevational view thereof.

I claim:

The ornamental design for a railway car shaker or similar article, substantially as shown.

YNGVE SODERBERG.
